UNITED STATES PATENT OFFICE.

ROBERT J. NICHOLSON, OF CHICAGO, ILLINOIS.

LOOSE-LEAF BINDER.

979,087.

Specification of Letters Patent. Patented Dec. 20, 1910.

Application filed May 14, 1909. Serial No. 495,958.

To all whom it may concern:

Be it known that I, ROBERT J. NICHOLSON, a citizen of the United States, residing at Chicago, in the county of Cook and State of Illinois, have invented a certain new and useful Improvement in Loose-Leaf Binders, of which the following is a full, clear, concise, and exact description, reference being had to the accompanying drawings, forming 10 a part of this specification.

My invention relates to loose-leaf binders of the kind in which two cover portions are employed, the cover portions being united by binding members that are in threaded 15 engagement.

In the preferred embodiment of my invention, the threaded binding members which are employed are in the form of threaded sleeves or posts carried by one of the cover 20 portions and screws for engagement with the threaded portion of the sleeves or posts and carried by the other cover portion.

It is the object of my invention to guard against the separation of those members 25 which are adapted for engagement with the threaded posts or sleeves from the cover portion carrying the same, whereby when the binding members are separated, in order to permit of the insertion of leaves within the 30 loose-leaf binder, or the removal of such leaves, the binding members carried by each cover portion are readily adapted to register and be engaged with the binding members carried by the other cover portion.

In the preferred embodiment of my invention, I employ a holder for the threaded posts or sleeves and a holder for the threaded elements complementary to said posts or sleeves, these holders being bound within the 35 cover portions which are suitably apertured to enable the binding members carried by the cover portion to reach and have engagement with the binding members carried by the other cover portion. The holder for 40 the binding members complementary to the threaded posts or sleeves are provided with means whereby said complementary binding members are prevented from being shifted materially from their axes of rotation and 45 materially from the planes they occupy, so that said complementary binding members are always in position to be engaged with the threaded posts or sleeves and are not likely to be lost when the binding members 50 are disunited.

I will explain my invention more fully by

reference to the accompanying drawing, showing the preferred embodiment thereof, in which—

Figure 1 is a perspective view of the binding mechanism. Fig. 2 is a view similar to Fig. 1, except that the parts are shown in sectional elevation. Fig. 3 is a longitudinal sectional view through the cover portions and a pair of binding members employed to 60 unite the cover portions. Fig. 4 is a view similar to Fig. 3, except that the cover portions are shown in separated relation.

Like parts are indicated by similar characters of reference throughout the different 70 figures.

The cover portions *a* and *b* are of any suitable formation, and, in the instance illustrated in the drawing, are themselves unjoined except through the agency of the 75 threaded posts or sleeves *c* carried by one of the covers and the complementary binding members *d*, that are desirably in the form of screws that engage the threaded bores of the sleeves *c*. I do not wish to be limited, however, to a construction in which the cover portions *a* and *b* depend only upon the members *c* *d* for uniting the same. In the embodiment of the invention illustrated, the cover portion *a* carries a holding plate or 80 holder *e* upon which the sleeves *c* are mounted, these sleeves being suitably secured in any convenient manner, to the holding plate *e*. The cover portion *b* has a holding plate or holder *f* bound therein, this latter plate 85 being apertured to permit the shanks of the screws *d* to pass therethrough, the ends of the holding plate *f* being overturned to overlie the slotted heads of the screws *g*, sufficient clearance intervening between the overlapped ends of the plate *f* and the balance of the plate to prevent the screw heads from 90 being bound, the apertures in the plate *f* through which the shanks of the screws *g* pass being also sufficiently large to permit a 95 limited freedom of movement of the shanks of the screws *g*, so that these shanks may be brought into register with the threaded bores of the sleeves *c*. The cloth or other material which surrounds the plates or holders *e* and *f* is suitably apertured to permit the posts or sleeves *c* to project through the cover portions, the cover portion *b* being further apertured to permit of the access of an operating 100 tool to the binding members *d* when it is desired to unite the binding members *c* and *d* or to separate the same. When the binding 110

members are separated, the screws cannot be lost, inasmuch as their relationship with the cover portion *b* carrying the same is permanent.

5 While I have herein shown and particularly described the preferred embodiment of my invention, I do not wish to be limited to the precise construction illustrated, as changes may readily be made without departing from the spirit of my invention.

10 Having thus described my invention, I claim as new and desire to secure by Letters Patent the following:—

15 1. A loose leaf binder including cover portions between which loose leaves may be disposed, a post carried by one cover portion, acting as a binding member, a complementary binding member carried by the other cover portion and adapted to be engaged with and separated from the aforesaid binding member, and a folded plate for holding the complementary binding member in position with respect to the cover portion carrying the

same, the outermost layer of said folded plate being apertured or recessed to permit of access therethrough to said complementary member. 25

2. A loose leaf binder including cover portions between which loose leaves may be disposed, a post carried by one cover portion, 30 acting as a binding member, a binding screw in threaded engagement with said post and carried by the other cover portion, and a folded plate for holding the complementary binding member in position with respect to the cover portion carrying the same, the outermost layer of said folded plate being apertured or recessed to permit of access therethrough to said complementary member. 35

In witness whereof, I hereunto subscribe 40 my name this fifth day of May A. D. 1909.

ROBERT J. NICHOLSON.
